(57) CLAIM

The ornamental design for a decorative shower hair wrap as shown and described.

DESCRIPTION

FIG. 1 is a front left perspective view of a decorative shower hair wrap of the instant invention;
FIG. 2 is a left side view thereof;
FIG. 3 is a right side view thereof;
FIG. 4 is a top view thereof;
FIG. 5 is a bottom view thereof;
FIG. 6 is a front view thereof;
FIG. 7 is a back view thereof; and,
FIG. 8 is a front perspective view of the decorative shower hair wrap in a position of use, as it may appear on a user. The broken line outline of the partial human figure in FIG. 8 assists in illustrating how the decorative shower hair wrap may appear when in a position of use, but forms no part of the claimed design.
